UNITED STATES PATENT OFFICE.

WILLIAM E. WOODARD, OF FOREST HILLS, NEW YORK, ASSIGNOR TO FRANKLIN RAILWAY SUPPLY COMPANY, A CORPORATION OF DELAWARE.

LOCOMOTIVE DRIVING-BOX STRUCTURE.

Application filed February 12, 1921. Serial No. 444,565.

This invention relates to locomotive driving boxes and has special reference to an arrangement which admits of the applying and withdrawing of the driving box cellar with indicator rods in place, without disturbing or removing the driving box spreader or dismantling the cellar and the contained parts.

Another object of the invention relates to the provision of improved means for holding the cellar and the end plate in position whereby the pin, which secures the same, cannot be distorted. This frequently occurs in standard arrangements now in use and is a source of annoyance and expense because the distorted and jammed pin must be removed in order to withdraw the cellar or to supply fresh lubricant, and new pins must ordinarily be substituted for the distorted ones.

Still another object of the invention resides in the provision of an arrangement whereby, when the locomotive is lifted with driving wheels in place, no load is imposed on the cellar, as is the case in standard constructions. The breakage of the cellar box which frequently results from this cause in standard constructions is thus eliminated.

My invention also contemplates an improved arrangement whereby the parts may be readily adjusted to compensate for changed conditions resulting from wear, as will further appear.

The foregoing, together with such other objects as may hereinafter appear, or are incident to my invention, I obtain by means of a construction which I have illustrated in preferred form in the accompanying drawings, wherein:

Fig. 1 is a side elevation of a driving box equipped with my improvements, such improvements being shown in section on the line 1-1 of Fig. 2; Fig. 2 is a section through my improvements taken on the line 2-2 of Fig. 1; Fig. 3 is an end elevation of the parts shown in Fig. 2 as applied to a box; Fig. 4 is an end elevation of my improved form of spreader as seen when looking at the left hand end of Fig. 2; and Fig. 5 is a fragmentary section illustrating a modification of my invention.

Referring now to Fig. 1, the reference number 7 indicates the driving box which has the usual brass 8 for the axle 9. The jaws of the driving box are held against

"pinching" or inward flexure under load, by the spreader indicated as a whole by the reference letter A, the construction of which will shortly be described. The driving box cellar is indicated by the reference number 10 and it may be of any preferred general construction, such, for example, as illustrated in the United States patent to Martin, 1,268,748 of June 4, 1918. The driving box cellar 10 has the usual follower plate 11, lubricating spring 12 and lubricating pad 13. The grease cake is inserted between the follower plate 11 and the lubricating pad and the condition of the cake is indicated by the rods 14 which depend below the bottom of the cellar.

The spreader A comprises an open frame, substantially rectangular in shape, and it is secured to the box at its outer edge next to the driving wheel with a single long bolt 15. The separation of the transverse compression-resisting portions or members of the frame affords opening for downward projection, and observation, of the indicating rods 14. It is secured at its inner edge next to the center line of the locomotive by two short bolts 16 (see Figs. 1 and 2). The inner compression member 17 of the spreader is dropped down or recessed in its upper side at the center line of the driving box and is, in effect, somewhat V-shaped in order that it may clear and afford passage across it for the indicator rods, thereby permitting the cellar to be placed in position and withdrawn laterally along the spreader structure away from the adjacent driver without removal of the spreader.

The cellar 10 rests upon the top of the spreader and near its outer side it is provided with a depending lug 18 (see Fig. 2) which abuts against a side of the spreader and limits the outward movement of the cellar.

The cellar is maintained in position by the end plate 19 which also serves to close the open end of the cellar. The closure plate 19 is held in position by a single pin 20 which passes through the lugs 21 and 22 on the inner face of the member 17 of the spreader (see Figs. 2 and 3). The end closure plate 19 is also provided with a pair of ears 21^a and 22^a which are grooved as at 23, such grooves coming into alignment with the pin apertures in the lugs 21 and 22 when the end closure plate is brought in proper posi-

tion. When the pin 20 is in position the closure plate will be securely held against vertical movement and also against movement away from the spreader. The closure plate is also held as against displacement across the face of the spreader and cellar. The shoulders 24 and 25 on the closure plate respectively are adapted to rest on the lugs 21 and 22 thereby relieving the pin 20 of load, particularly when the locomotive is lifted with the drivers in place. It will be seen that when this is done the end closure plates, which are concave at the top to fit the axle, will take the load of the axles and drivers and transmit the same directly to the lugs 21 and 22 of the spreader. There is thus no tendency to distort the pins 20 and the difficulties heretofore noted are avoided.

In order to withdraw the cellar or to insert a new grease cake, it is only necessary to remove the pin 20 by withdrawing the key 27 which will permit of the removal of the closure plate 19. No other parts need be disturbed.

By carrying the closure plate 19 upwardly a little farther than the front wall of the cellar, the end closure plates will relieve the cellars of all load, when the locomotive is lifted with drivers in place and the breakages frequently occurring in standard practice where the load is taken by the cellars, are avoided. As the driving brass wears in service, the box is let down with respect to the axis of the axles and this may occur in an amount sufficient to permit of the lubricating pads clearing the top of the end closure plates and working out laterally. To meet such conditions, I have provided the modification shown in Fig. 5, from inspection of which it will be seen that the end closure plate 19 is supported on the member 17 by either one of two lugs 28 and 29, arranged on opposite sides of the plate in stepped relation. When the plate is reversed and it rests upon the lug 29 it will be seen that it will be shifted upwardly, thus compensating for the letting down of the box above referred to and ensuring the maintenance of the lubricating pad in place.

50 I claim:

1. The combination with a laterally removable driving box cellar having a grease follower plate and indicator rods projecting therebelow, of a driving box spreader for resisting inward flexure of the box jaws and means for securing it in position, the spreader and the securing means being so constructed and disposed as not to interfere, when in position, with the removal of the cellar with its indicator rods.

2. The combination with a driving box having a removable lubricating cellar with indicating means projecting therebelow, of a spreader for resisting inward flexure of the box jaws recessed at its upper side to afford

70 passage for the aforesaid indicating means when the cellar is shifted away from the adjacent driver to remove it from the box, and separate means for securing the cellar to the respective pedestal jaws.

75 3. In a driving box having a removable cellar with follower plate and indicator rods, a spreader for the box, separate from and independent of the cellar, recessed to permit removal of the cellar without removal of the spreader.

80 4. In a driving box having a removable cellar provided with indicating means projecting exteriorly, a spreader for the box recessed to clear the indicating means and to permit the removal of the cellar without removal of the spreader.

85 5. The combination with a driving box having a removable cellar with indicating means projecting therebelow, of a spreader for resisting inward flexure of the box affording passage for said indicating means across its compression portion when the cellar is shifted along the spreader structure for removal from the box.

90 6. A spreader for a driving box with removable cellar comprising a structure with portions for resisting transverse compressive stress separated to afford an opening for downward projection and observation of the cellar indicating means, one of said portions being recessed at its upper side to afford passage for the indicating means thereacross when the cellar is removed from the box.

100 7. In a driving box having a lubricating cellar, the combination of a spreader for the box and means for retaining the cellar in place detachably secured to the spreader.

105 8. In a driving box having a lubricating cellar, with an open end for the insertion of lubricant, the combination of a spreader for the box and a cover plate for said open end detachably but fixedly secured against the corresponding end of the spreader.

110 9. In a driving box having a cellar, the combination of spreader means for the box secured thereto, and means for transmitting the load of the axle and drivers to the spreader independently of the cellar when the locomotive is lifted with drivers in place.

115 10. The combination of a driving box, a cellar therein beneath the driver axle, and means for transmitting the load of axle and drivers to the driving box independently of the cellar when the locomotive is lifted with drivers in place.

120 11. In a driving box having a cellar, the combination of a spreader, means for attaching the spreader to the box, a retaining member for the cellar forming an end closure therefor, and means for detachably but fixedly securing the retaining member to the spreader.

125 12. The combination with a driving box

- structure comprising a driving box proper and a spreader therefor, of a lubricating cellar in the box beneath the driver axle, and a cellar-retaining member for transmitting load of axle and drivers to the driving box structure independently of the cellar when the locomotive is lifted with drivers in place.
13. The combination with a driving box having a lubricating cellar removable from the box lengthwise of the axle, of a retaining member for said box adjustable in elevation to compensate for variation in vertical position of the axle in the box with wear of the latter.
14. The combination with a driving box having a lubricating cellar open at the end and removable from the box lengthwise of the axle, of a retaining end closure plate for said cellar and box vertically adjustable relatively to the latter.
15. In a driving box having a lubricating cellar, a retaining member for the cellar, and means whereby the retaining member may be adjusted in elevation, said retaining member being adapted to take the load of the axle and drivers when the locomotive is lifted with the drivers in place.
16. In a driving box having a lubricating
- cellar, the combination of means for relieving the cellar of the load of the axles and drivers when the locomotive is lifted with the drivers in place, and means whereby said first means may be adjusted.
17. In a driving box having a cellar, the combination of a spreader for the box and a member for taking the load of the axles and drivers when the locomotive is lifted having a plurality of stepped means each of which is adapted to serve as a means for supporting said member on the spreader.
18. In a driving box having a lubricating cellar, a spreader for the box located below the cellar, said spreader comprising an open frame, the inside side of which is approximately V-shaped and depends from the remaining portion of the frame.
19. In a driving box having a lubricating cellar, a retaining member therefor, said retaining member having a plurality of serial or stepped means any one of which may be used to engage an adjacent part of the box to support the retaining member in desired positions of adjustment.

In testimony whereof, I have hereunto signed my name.

WILLIAM E. WOODARD.
